Fig. 5.

A technical cross-sectional drawing of a mechanical assembly. The drawing shows a central vertical axis with a rectangular frame. At the top, a component labeled 57 is shown. Below it, a component labeled 53 is attached. A horizontal rod labeled 51 extends from the center. A curved component labeled 56 is positioned below the rod. A vertical component labeled 58 is on the left side. A base labeled 59 is at the bottom. A label 55 is located at the bottom right. A label 48 is on the right side, pointing to a horizontal line. The drawing uses various hatching and cross-hatching to differentiate parts.

UNITED STATES PATENT OFFICE.

HENRY C. FENKER, OF ALLEGHENY, PENNSYLVANIA, ASSIGNOR OF ONE-HALF TO LUDWIG KELEMEN, OF ALLEGHENY, PENNSYLVANIA.

RAILWAY-SWITCH.

No. 839,743.

Specification of Letters Patent.

Patented Dec. 25, 1906.

Application filed September 27, 1905. Serial No. 280,397.

To all whom it may concern:

Be it known that I, HENRY C. FENKER, a citizen of the United States, residing at Allegheny, in the county of Allegheny and State of Pennsylvania, have invented certain new and useful Improvements in Railway-Switches, of which the following is a specification.

This invention relates to new and useful improvements in so-called "automatic" switches—that is to say, improvements in track devices which, in combination with means carried by the locomotive and operable from the cab thereof, throw the switch to one side or the other to run the train on the straight track or upon a siding; as may be desired, without the necessity of stopping the train.

I am aware that switches having the same general purpose in view have been invented; but they have usually been so complicated and unreliable as to prohibit their adoption.

In the invention about to be described it will be noted that the mechanism is exceptionally simple and inexpensive and so positive in operation that it cannot fail so long as the engineer or other person in the cab sets the engine devices to throw the switch to desired position.

The primary object of my invention is to save the time usually lost in sending a man forward to open the switch upon the approach of the train and the time consumed in resetting and locking the switch after the train has passed.

The invention about to be described is also designed to prevent accidents or other disasters which frequently occur as a result of the consumption of too much time in opening and closing switches when, for instance, a freight-train drops back on the time of a passenger or other fast train.

A further object of the invention is to so construct the mechanism that the switch can also be operated by hand in the usual manner, if it is found desirable.

The invention consists, in the main, of a novel mechanism carried by the locomotive, a part of which is securely attached to the locomotive in advance of the front wheels of the front truck, which forward part of this particular mechanism has connection with an operating-lever in the cab located in convenient position to be manipulated or oper-

ated by the engineer or other person whose duty it may be to take care of the switches, and a mechanism located adjacent to the track and having connection with the switch-points, which mechanism when engaged by the locomotive devices will invariably and positively throw the switch-points to one side or the other, as may be required to run the train on the straight track or open the siding for the purpose of permitting the train to take the siding when necessary. The mechanism carried by the locomotive, as will be described farther on, is so constructed as to make it possible to avoid entirely the track devices, so that the train may pass the switch without operating it, as in a case where the switch is already set in proper position for the approaching train. Then, too, the construction is such that the engineer, knowing the track he wants, can set his lever to take the particular track regardless of the position of the switch as known to him, and if the switch happens to be wrong for his train it will be thrown to right position, thus making it impossible to take a track which is not wanted so long as the operating-lever is correctly set in advance.

Other objects and advantages of the invention resulting from the construction about to be described will become apparent to those experienced in railroading, and the points of novelty will be pointed out in the claims.

Referring to the drawings, Figure 1 shows a section of a track with my improved devices in connection therewith in side elevation, the locomotive being in dotted lines in side elevation, showing the general arrangement of the mechanism or parts carried by the engine, the parts being in full lines with both contact devices or rollers raised equidistant above the tracks or in position where they will pass over the switch-operating device without causing the switch to be operated. Fig. 2 is an enlarged side elevation of a section of the track and track devices, showing also in side elevation the mechanism carried by the engine, a dotted position of the operating-lever and its connection being shown, in which one of the contact-rollers is brought to a position to operate the switch. Fig. 3 is a plan view of a track-section, showing the switch set for what I will hereinafter term the "straight track." Fig. 4 is a simi-

- lar view showing the track set for what will be termed hereinafter the "siding." Fig. 5 is an enlarged transverse section taken on line $x-x$, Fig. 3, looking in the direction of the arrow. Fig. 6 is a similar section taken on the line $y-y$, Fig. 4, also looking in the direction of the arrow; and Fig. 7 is a top plan view of the switch-weight and lower section of the weight-casing; and Fig. 8 is an enlarged perspective view of the parts carried by the engine, consisting in the main of the operating-lever, the contact devices, and the connections between the lever and said devices.
- 15 In the drawings the numeral 1 designates the operating-lever, pivoted upon any suitable support, as 2, in the locomotive-cap, the lever being provided with a finger-lever 3, connected with a slide 4, adapted to enter one or the other of the notches 5 in the segment 6, which segment is rigidly secured upon a suitable support in the cab. The operating-lever 1 is extended below its pivotal point 2, as indicated by the numeral 7, and terminates in a bifurcated end 8, to which is pivoted at 9 a connecting-rod 10, which rod has its forward end pivotally connected at 11 to the arm 12 of a bell-crank lever 13, mounted on the squared end of a transverse rock-shaft 14, which is mounted pivotally in suitable supports upon the forward part of the engine-frame. This bell-crank lever 13 has pivotally connected to its other arm 15 the upper end of a short rod 16, which rod has a yoke 17 at its lower end, in which is pivoted a contact-roller 18. The rod 16 passes through a slightly-elongated slot 19 in the forward end of an arm 20, which arm extends rearwardly, where it terminates in a flat pivoted plate 21. The rock-shaft 14 at the end opposite from that just described carries a short arm 22, to which is pivoted a short rod 23, like the rod 16, and the construction described with regard to the yoke 17 is duplicated and a contact-roller 24 is provided to perform the same functions as the roller 18. The arm 23, like the arm 20, passes through a slot 25 in the forward end of the rod 26, and like the rod 20 terminates at its rear end in a flat pivoted plate 27. The rods 20 and 26 are for the purpose of holding the contact-rollers firmly to their work when one or the other of the arms or rods 16 and 23 are in vertical position, or in position in which the switch devices will be operated. However, as clearly shown in Fig. 8, these rods do not prevent the rollers from being lifted above the track devices, the position of the rod 20 being that which it will occupy when the contact-roller is lifted. The operating-lever is preferably so arranged normally with relation to the rock-shaft 14 and the parts carried thereby that when the slide 4 is in the central notch of the segment 6 both contact-rollers will be lifted to the same height, in

which position they will entirely clear or escape those parts of the switch-operating devices that are on the track, and the train will pass over the switch without operating the same. I have so arranged the whole mechanism that when the operating-lever is pushed to the extreme forward position and there locked the contact-roller on the right side of the engine will engage the track device and throw the switch for the siding, and when the lever is in its extreme rear position obviously a reverse operation will result. However, I desire it understood at the outset, and it is obvious, that this arrangement may be changed or reversed and any predetermined operation of the switch, whether to avoid the track devices entirely or to operate the same from one or the other side of the track, may be brought about by changing the normal positions of the parts. 85

Having described the mechanism carried by the locomotive or engine, I will now describe in detail what I have heretofore referred to as the "track devices"—that is to say, the equipment of the track—which, in combination with the engine devices, serve to throw the switch to one side or the other as the exigencies of the case may require.

Referring more particularly to Figs. 3, 4, 5, and 6, the numerals 28 and 28' represent two arms pivoted at 29 between the upturned portions or ears 30 of two rigid plates 31, which are firmly secured to the extensions 31' of two cross-ties 32. These arms 28 and 28' are each provided with a curved arm 32, ranging in the direction of the approach of the engine. The arms 28 and 28' are each further provided with short depending arms 33, (clearly shown in Figs. 2 and 5,) to which are pivoted at 34 the opposite ends of a transverse arm 35, which has a central enlargement 36, recessed for the reception of the switch-throwing arm 37, which is pivoted to the arm 35, as shown at 38. The switch-throwing arm 37 is pivoted at 39 to a cross-tie 40 and extends forward, where its other end is pivoted in a recess 41 in an enlargement 42, formed centrally in the transverse arm 43. The arm 43 has its outer end attached to the movable switch-points 44 and 45. The arm 43 has integral therewith a short depending arm 46, to which is pivoted at 47 the inner end of a rod 48. The outer end of the rod 48 is pivoted at 49 to a short arm 50, which forms a part of the switch-setting or weight-throwing device 51. This device is pivoted upon a bolt 52, having bearings in ears 53, formed upon a base-plate 54, which is provided with a curved slot 55, in which works a transverse pin 56, which pin connects the arms 57 of a switch-weight 58. The arms 57 of the switch-weight are also pivoted on a bolt 52. The arrangement of the switch-setting device 51 with relation to 130

the weight is such that when the weight is thrown by a sudden movement of the device through the medium of arm 48 the pin 56 will be suddenly moved from its last position 5 and thrown over, thus bringing said pin to the other end of the slot, where the weight will hold the switch set. In Fig. 6 a dotted position of this mechanism clearly shows the position of the parts after the switch has been 10 operated.

For the switch-setting device and weight and the parts directly connected with them I provide a casing 59, which may be of any approved construction and provided with 15 means for locking the same to prevent the switch from being tampered with. It will be understood that when the switch is to be operated by hand it will only be necessary to unlock the casing and throw the weight to 20 the desired position in the ordinary manner.

In Figs. 3 and 4 of the drawings I have shown in dotted lines, as indicated at 60, an arm like the arm 37, to the end of which, if found desirable, I may connect a transverse 25 arm like 35, which may in turn be connected with arms like 28 and 28', or, in other words, duplicate the mechanism on both sides of the switch-weight, so that the switch will be operated by an engine or train approaching the 30 switch from the direction opposite that in which the described mechanism would be operated; but this being mere duplication it is not deemed necessary to further illustrate the connections or to further describe 35 the modification.

The numeral 61 designates a curved guard, one of which I provide over each curved portion of the arms 28 and 28'. These guards are to prevent the direct contact of the rollers 40 18 and 24 with the curved portion of the arms. At one end each guard is rigidly attached, as at 62, to a plate or support 63; but in order that the guards may yield downwardly when engaged by the contact-rollers 45 on the engine I provide each with an elongated slot 64, through which passes a short bolt 65. The bolts 65, aside from passing through the slots, pass through small plates 66 and lower plates 67. The plates 66 are 50 not clamped tightly upon the slotted ends of the guards, but rest upon them in a manner that will permit the free movement of the guards. This movement, however, will be very slight, as it will correspond to the degree 55 of depression of the arms 28 and 28' when one or the other is depressed.

Having described the construction of the mechanism, its operation will now be described. Assuming the contact-rollers to be 60 in the position shown in full lines, Figs. 1 and 2, the switch will not be operated and the train will pass onto the track set for it, which track may be indicated by any well-known signals now in use. Assuming, further, the 65 switch to be in the position shown in Fig. 3, or

set to take the rails *a* and *b*, and it is then desired to take the rails *c* and *d*, the engineer or other proper person in the cab as the engine approaches the switch throws and sets the lever so that the contact-roller 18 is 70 thrown down to the position where it will engage the arm 28, or rather the guard resting upon the arm, which arm will be rocked upon its pivot 29 and will exert a sudden pull upon the transverse rod 35, which in turn 75 will rock the arm 37 on its pivot 39 and through the medium of said arm will exert a sudden pull upon the transverse arm 43, which by reason of its connection with the rod 48 will throw the switch-weight to the opposite end of the slot 55 from that which it formerly occupied, thus shifting the switch-points and holding them firmly in position.

It will be seen by reference to Fig. 6 that the arms 57 are each provided with a slightly- 80 elongated slot 57', through which the pin 56 passes, which gives the said pin a little play in said arms.

I claim—

1. In a railway-switch, the combination 90 with devices located adjacent to the track-rails, mechanism between said devices and the switch-points whereby the switch is operated with each operation of said devices, an operating-lever carried by the vehicle, a rock-shaft mounted on the vehicle, and having contact devices connected therewith, a connection between the operating-lever and the rock-shaft, whereby when the lever is operated one contact device is raised and the other 95 depressed, means for rigidly locking the operating-lever, pivoted arms operating in conjunction with the contact devices to hold them rigidly to their work when lowered to operate the switch, whereby the lever and 100 devices may be positively set in advance to take either the main track or the siding regardless of the known position of the switch.

2. In a railway-switch the combination 110 with means carried by the locomotive or train and under control of the engineer or other person on the train, a pivoted arm adjacent to each rail of the track and adapted to be engaged by the said means carried by the train, a transverse arm pivotally connecting each of said pivoted arms, connections between the transverse arm and the switch-points whereby the switch-points are shifted to one side or the other, when one or the other of the pivoted arms is engaged by the 115 train means, and a switch-weight connected with the switch-points and adapted to be thrown when the switch is operated to set the switch, substantially as described.

3. In a railway-switch, the combination 125 with means carried by the locomotive or train, a pivoted arm adjacent to each rail of the track and adapted to be engaged by the said means carried by the locomotive or train, a transverse arm pivotally connected 130

- to each of said pivoted arms, a switch-throwing arm as 37, having connection with the transverse arm and switch-points whereby the switch-points are thrown to one side or the other when the first-mentioned pivoted arms are rocked, and a suitable switch-weight so connected with the switch-points as to set them in one position or the other when the switch is operated.
4. In a railway-switch, the combination with an operating-lever carried by the locomotive, a rock-shaft also carried by the locomotive and having contact-rollers connected therewith, a connection between the operating-lever and the rock-shaft, whereby when the lever is operated one or the other of the contact devices is raised or depressed, or both of said contact devices raised for the purpose set forth, a pivoted arm adjacent to each rail of the track and adapted to be engaged by one or the other of the contact devices carried by the engine, a transverse arm as 35 pivotally connected to the pivoted arm, suitable connection between the transverse arm 35 and the switch-points whereby they are thrown to one side or the other when one or the other of the pivoted arms is engaged by said contact devices, and a suitable switch-weight having suitable connections with the switch-point whereby it is thrown with each operation of the switch and holds the same set, substantially as described.
5. In a railway-switch, the combination with the operating-lever carried by the locomotive, a rock-shaft mounted upon the locomotive and having contact devices connected therewith, a connection between the operating-lever and the rock-shaft, whereby when the lever is operated one or the other of the contact devices is raised or depressed or both of said devices raised for the purpose set forth, means for holding the contact de-

vices rigidly to their work when lowered to operate the switch, devices located adjacent to each rail of the track and adapted to be engaged by one or the other of the contact devices, an arm connecting said devices, connections between the arm and the switch-points whereby they are thrown or shifted when one or the other of the devices is engaged by said contact devices, and means for automatically setting the switch in its thrown position, substantially as described.

6. In a railway-switch, the combination with means carried by the locomotive or train, and under control of the engineer or other person thereon, a pivoted arm adjacent to each rail of the track and adapted to be engaged by the said means carried by the locomotive or train, a transverse arm pivotally connecting the pivoted arms, a pivoted switch-throwing arm connected at one end with said transverse arm and having connection with the switch-points whereby the switch-points are thrown or shifted to one side or the other when the first-mentioned pivoted arms are rocked, a suitably-protected pivoted switch-weight formed with two arms connected by a cross-rod, a pivoted device mounted upon the shaft of the switch-weight and having a slot therein through which passes the connecting-rod, and an arm pivotally connected with the pivoted device, said arm being also in pivotal connection with the switch-points whereby the switch-weight is thrown upon each operation of the switch to maintain the switch in position substantially as and for the purpose set forth.

In testimony whereof I affix my signature in presence of two witnesses.

HENRY C. FENKER.
